MACHINERY FOR TRIMMING
PRINTING PLATES

William F. Huck, Richmond Hill, N. Y., assignor,
by mesne assignments, to R. Hoe & Co., Inc.,
New York, N. Y., a corporation of New York

Application March 5, 1935, Serial No. 9,408

19 Claims. (CL. 29—69)

This invention relates to a machine for cutting the straight edges of a curved printing plate and more particularly to power driven cutter members which are adjustably mounted on a supporting structure in cutting relation with the straight edges of said printing plate.

The principal object of the invention is to provide power driven cutters and means whereby said cutters may be arranged in a cutting relation with the straight edges of a printing plate and may also be adjusted to a plurality of positions to cut plates to any one of a plurality of dimensions as desired.

Another object is to provide a plurality of longitudinal grooves in a plate supporting member, also means which is adapted to maintain the cutters in a fixed cutting position with relation to the plate edges and said grooves in the supporting member.

It is a further object to provide a mounting for said power drive members whereby said members may be adjusted in an arcuate path concentric to the curve of the printing plate and further to provide a means for latching the power drive members in one of a plurality of positions to thereby cut a plate to any one of a plurality of dimensions as desired.

It is also an object to provide a machine for cutting the straight edges of a curved printing plate which is of generally improved construction, whereby the device will be simple, durable and inexpensive in construction, as well as convenient, practical, serviceable and efficient in use.

With the foregoing and other objects in view which will appear as the description proceeds, the invention resides in the combination and arrangement of parts, and in the details of construction hereinafter described.

The preferred embodiment of the invention is illustrated in the accompanying drawings, wherein:

Figure 1 is an end elevational view of a machine for cutting the straight edges of curved printing plates with the parts mounted thereon according to this invention, and showing a part thereof in section;

Figure 2 is a side elevation of the structure shown in Figure 1 as taken in the direction of the arrow 2 on Figure 1, with parts broken away; and

Figure 3 is an enlarged detail of the latching mechanism with parts broken away.

The machine generally comprises a frame structure, a portion of which is shown at 11 and a bed 12 secured to said frame. A longitudinal screw 13 has its ends rotatably mounted in bear-

ings 14, 15 secured to the bed structure, and has a hand wheel 16 secured at one end thereof.

A support 17 is adapted to have a printing plate P mounted thereon, and comprises a substantially semi-cylindrical member, having a wall 18 at each end thereof, and a screw threaded nut 19 formed at the lower portion of said wall, which nut is mounted on the longitudinal screw 13. Anti-friction rollers 21 are mounted on studs 22, extending inwardly from inner side wall portions 10 23—23 of the support 17, and ride on the upper surface of flanges 24—24 formed on the bed 12. Another set of anti-friction rollers 25 are mounted on studs 26 below the rollers 21—21 and engage the lower surface of the flanges 24—24. It 15 will thus be seen that when the longitudinal screw 13 is rotated by means of the handwheel 16, the support 17 is adapted to be freely moved along the bed 12. Said plate support 17 is also provided with a number of longitudinal grooves 20 27 along each side thereof for a purpose which will be hereinafter referred to.

The plate P rests upon the outer surface of the support 17 and is adapted to be clamped thereon between a movable end clamp 28 and a stationary clamp lug 29 on said support. The said movable clamp has a screw connection with a screw member 31, and is slidable within a longitudinal guide-way 32 in the upper surface of the plate support 17, the screw being mounted in suitable end bearings 33—34 secured to the said support. A hand wheel 35 is provided at the outer end of the screw member 31 to rotate same and thereby move the clamp 28 into or out of a plate clamping position.

Another supporting structure is provided at the forward or left hand end of the machine as viewed from Figure 2, which preferably comprises two curved side arms or wings 36—36, which are preferably integrally joined at their lower ends and are secured to a pad 37 on the frame 11. Curved ways 38—38 are provided on the arms 36, which ways are concentric with the axis or curved surface of the plate support 17 and may be constructed in any desirable manner, the construction shown comprising curved straps 39—39, 45 which are secured to the arms 36—36 and have undercut portions 41—41. Said arms 36—36 are supported in a stationary position and are arranged in an equidistant spaced relation to each side of the plate support 17 to permit the said plate support to pass therebetween when the handwheel 16 and longitudinal screw 13 are rotated. On the outer peripheral surface of the arms 36—36, a number of lugs or dogs 42 are mounted, each of which has an upwardly project- 50 55

ing nose 43, and each lug is adjustably secured to the arms 36 by means of a bolt 44, which passes through a clearance opening 45 therein, as shown in Figure 3. A screw 46 provided for each lug, has a screw connection with the rear end of a lug and is also rotatably mounted in an anchor stud 47 on the periphery of the arm. Thus, by loosening the bolt 44 and rotating the screw 46, the lug 42 may be adjusted.

10 Two rotary cutters 48-48 are provided to cut the straight edges 49-49 of the plate P simultaneously, each cutter being mounted at the ends of motor drive shafts 51-51 of their respective driving motors 52-52. Each motor is mounted 15 on bracket members 53-53 and each bracket member has an arcuate portion which is slidably mounted within the arcuate ways 38-38. Extending outward from each bracket is an arm 54, which has a bearing 55 formed thereon and is also shaped to provide a grip handle 56. A shaft 51, rotatably mounted within each bearing 55, has an eccentric portion 58 thereon. A latch member 59 is rotatably mounted on the eccentric portion 58 of said shaft 51 and is confined between a flange 60, at the end of said eccentric, and the end of the bearing 55. The end of the shaft 51 opposite the eccentric, extends beyond the bearing 55 and has a hand lever 50 secured thereto to rotate same, and thereby adjust the position of said latch. The 30 said shaft is also adapted to be locked against rotation after an adjustment is made, by means of a bolt 61, which passes through a bore 62 in the shaft, and which is adapted to be drawn up tight by means of a handle 63 which has a screw connection with a threaded end on said bolt.

The latch 59 has a hook 64 provided thereon at its outer end, which is adapted to become engaged with a nose 43 of one of the lugs 42 and is further provided with means to normally bias said hook toward the lugs 42. Said biasing means includes a strap 65 which has one end secured to the latch, while the opposite end thereof is bent outward into alignment with the grip handle portion 56 of the bracket member 53, and has a flat spring blade 66 secured thereto, which springs bears against said grip handle 56.

As previously stated, the machine is adapted to cut the straight edges of curved plates and to cut said plates to any one of a plurality of dimensions 50 as desired. Before cutting the longitudinal grooves 21 in the plate support 17, the number of various sizes of plates, which it is desired to cut, are first determined, and one groove is cut on each side of the plate support for each of the various sizes of plates at a point which coincides with the line upon which the edges of the plate are to be cut, the width of the groove being sufficiently large 55 to provide clearance on each side of the cutter. In Figure 1, the three lowermost grooves indicated at 21a, 21b and 21c are provided for the cutting of three individual sizes of plates, the lower grooves 21a being provided for plates, the edges of which are approximately 180° apart, and the grooves 21c being provided for plates, the edges of 60 which would be about 120° apart. When positioned on a printing cylinder, the 180° plates would require two plates to a cylinder while the 120° plates would require three plates to a cylinder. The uppermost grooves are shown wider 65 than the others to provide for two sizes of plates which are not sufficiently different in the dimension between the edges to permit separate slots to be cut.

One lug 42 is provided for each edge of plates of 70 different dimensions, there being six lugs pro-

vided in the set-up shown in Figure 1 on each arm 36, with each lug, positioned in such definite relation to the grooves 21 in the plate support, that when the latch 59 is in engagement with a lug 42, a cutter 48 is in the correct cutting position. If it should become necessary to adjust the position of the cutter to maintain the desired clearance relation with respect to a groove 21, any minor adjustments can be quickly made by releasing the clamping handle 63 and adjusting the 10 position of the eccentric 58 by means of the hand lever 50. This adjustment will raise or lower the normal position of the hook 64 and thus lower or raise the respective position of the motor bracket 53 and the cutter 48. 15

It will be observed that the latch members 59 and their associated lugs 42 are the only means required to secure the cutter and power drive members in an operating position. The weight of the motor and its supporting bracket, assisted 20 by the force of gravity tend, to pull the hook 64 against the nose 43 of the lug 42, which thus rigidly supports the power drive in position. When the power drive is to be moved to another position, the motor and its supporting bracket have 25 to be lifted a sufficient distance, by means of the grip handle 56 before pressing on the strap 65, to permit the latch hook 64 to swing clear of the nose 43.

A gage is also provided at each side of the plate 30 support to determine the line upon which a cut is to be made on the printing plate P. Each gage comprises a bracket 67 which is pivotally mounted on a shaft 68, the latter having one end screwed within the motor support bracket 53, and is normally biased away from the surface of the printing plate P, by means of a coil spring 69 around said shaft, which spring has one end in engagement with a portion of the gage bracket, and its opposite end in engagement with a collar 71 on 40 the shaft 68. A stop member 72 projects outward from the collar 71 and into the path of a part of the gage bracket 67, to thereby fix the normal position of said bracket away from the printing plate. A straight edge blade 73 is ad- 45 justably mounted on the upper end of the bracket with its straight edge in alignment with the cut which is to be made, and is secured to said bracket by means of bolt and nut connections 74-74. It will be noted from Figure 2, that the position of 50 the gage is such as to permit the said straight edge to contact the surface of the printing plate P, to determine the cutting line, while the cutter is a certain distance away from the end of the plate P. It will be understood that the gages will 55 remain in the upright position shown in Figures 1 and 2 only while held in such position by an operator, otherwise they will normally remain in the dotted line position indicated at 67a, Figure 1.

It will be understood that the invention may 60 be embodied in other specific forms without departing from the spirit or essential attributes thereof, and it is therefore desired that the present embodiment be considered in all respects as 65 illustrative and not restrictive, reference being had to the claims rather than to the foregoing description to indicate the scope of the invention.

What I claim is:

1. In a machine for cutting the straight edges of a curved printing plate, a support for said plate, cutting means arranged in cutting relation with each straight edge of the plate, said support and cutting means being in longitudinally movable relation with one another, means to adjust said cutting means along an arcuate path 75

concentric to the curved surface of the plate to adapt same for cutting plates of a plurality of arcuate widths, and means for maintaining said cutting means in an adjusted position.

5. 2. In a machine for cutting the straight edges of a curved printing plate, a support for said plate, cutting means arranged in cutting relation with each straight edge of the plate, a support for each of said cutting means, and means to adjust each of said cutting means along its support in an arcuate path concentric to the curve of the printing plate.

3. In a machine for cutting the straight edges of a curved printing plate, a support for said plate, cutting members arranged in cutting relation with each straight edge of the plate, a drive for each cutting member, a bracket member for each of said drives, and supporting members having arcuate ways thereon concentric with the 20 curved surface of the printing plate and adapted to have said cutter drive bracket members adjustably mounted thereon, whereby the cutting members may be adjusted to a plurality of positions along said ways to cut a plate to any one of a plurality of dimensions as desired.

4. In a machine for cutting the straight edges of a curved printing plate, a curved support for the plate, a member having arcuate ways concentric with the axis of the support, and a power driven cutter rotatably supported on a bracket member, said bracket member being adjustable to a plurality of positions along the ways to dispose said cutter in position to cut a plate to any one of a plurality of dimensions in respect to its 35 width as desired.

5. In a machine for cutting the straight edges of a curved printing plate, a curved support for the plate, a member having arcuate ways, concentric with the axis of the support, power driven cutting members arranged in cutting relation with each edge of the plate, a bracket member for each power driven cutting member, said bracket members being adjustable to a plurality of positions along said ways, and means to maintain 40 said brackets in an adjusted position.

6. In a machine for cutting the straight edges of a curved printing plate, a curved support for the plate having a plurality of longitudinal grooves in the peripheral surface thereof, power driven cutting members arranged in cutting relation with each edge of the plate, a bracket member for each power driven cutting member, a member having arcuate ways concentric with the axis of the curved support and adapted to have said bracket members adjustably mounted thereon and latching means adapted to latch said brackets in a plurality of positions wherein the cutter positions will correspond with the grooves in the curved support.

7. In a machine for cutting the straight edges of a curved printing plate, a curved support for the plate having a plurality of longitudinal grooves in the outer surface thereof, motor driven cutter members arranged in cutting relation with each edge of the plate and in rotatable relation within the grooves, a bracket member for each motor, a member having arcuate ways concentric with the axis of the curved support and adapted to have said bracket members adjustably mounted thereon, lugs projecting outward from said bracket supporting member, and a latch carried by each of said motor bracket members, whereby the said brackets may be set in a fixed position in relation to the bracket supporting member with the cutters in a plate edge cutting position.

8. In a machine for cutting the straight edges of a curved printing plate, a frame, a support for said printing plate longitudinally movable along said frame, wings extending outward from each side of said frame and having arcuate ways concentric with the curve of the printing plate, motor driven cutter members arranged in cutting relation with each straight edge of said plate, and brackets to support each motor, said brackets being adjustably mounted on the ways in said wings. 10

9. In a machine for cutting the straight edges of a curved printing plate, a longitudinally movable support for said plate, means for supporting cutters in a cutting relation with the straight edge of said plate while the plate support is 15 moved, said means including a supporting structure having arcuate ways concentric with the curve of the printing plate and arranged at either side of said plate support, a power drive for each of said cutters, a bracket member associated with each power drive and being slidably mounted on said ways, and means to fix said bracket in any one of a number of predetermined positions, whereby a plate may be cut to any one of a plurality of dimensions as desired.

10. In a machine for cutting the straight edges of a curved printing plate, a support for said plate, means for supporting cutters in a cutting relation with the straight edges of said plate including a supporting structure having arcuate ways 30 concentric with the curve of the printing plate and arranged at either side of said plate support, a power drive for each of said cutters, a bracket member associated with each power drive and slidably mounted on said ways, a plurality of lugs 35 on said supporting structure, and a latching member associated with each power drive and adapted to be latched to any of said lugs to place the cutters in one of a plurality of plate cutting positions.

11. In a machine for cutting the straight edges of a curved printing plate, a support for said plate having a curved bearing surface and having a plurality of clearance grooves in said surface, means for supporting cutters in a cutting relation with the straight edges of said plate including a supporting structure having arcuate ways concentric with the curve of the printing plate and arranged at either side of said plate support, a power drive for each of said cutters including a 45 motor adjustably mounted on each of said ways, and means to latch said motors in one of a plurality of positions including lugs on said motor supporting structure, and a latching member associated with each motor which is adapted to be latched to said lugs to thereby accurately position each cutter in a cutting relation with the plate edge and in a clearance relation with the 50 said clearance slots in the curved support.

12. In a machine for cutting the straight edges of a curved printing plate, a support for said plate having a curved bearing surface and having a plurality of clearance grooves in said surface, means for supporting cutters in a cutting relation with the straight edges of said plate including a supporting structure having arcuate ways concentric with the curve of the printing plate and arranged at either side of said support, a power drive for each of said cutters including a 55 motor adjustably mounted on each of said ways, a gage associated with each cutter and having a straight edge aligned with the cutting edge of the cutter to determine the cutting position of said cutter, and adjustable latching means to latch 70 said cutter, and adjustable latching means to latch 75

said motor in any of a number of accurate cutting positions.

13. In a machine for cutting the straight edges of curved printing plates of different widths, a support for said plates, cutting means arranged in cutting relation with each straight edge of the plate, a support for each of said cutting means, and means whereby each of said cutting means may be independently adjusted in an arcuate path 5 concentric to the curve of the printing plate to thereby adapt said cutting means for cutting plates mounted on said support to any one of a plurality of dimensions as desired.

14. In a machine for cutting the straight edges 15 of curved printing plates of different widths, a support for the plates, power driven cutting means arranged in cutting relation with each straight edge of the plate, and means to adjust each of said cutting means independently of the 20 other along a path concentric to the axis of the curved plate, to cut plates mounted on said support to any one of a plurality of dimensions as desired.

15. In a machine for cutting the straight edges 25 of a curved plate, a support for the plate, said support being mounted for movement parallel to the straight edges of the plate, and a rotary cutter movable toward and away from a straight edge of the plate in an arcuate path concentric 30 to the curvature of the plate.

16. In a machine for cutting the straight edges 35 of a curved plate, a support for the plate, said support being mounted for movement parallel to the straight edges of the plate, a rotary cutter disposed adjacent each straight edge of the plate, each of said cutters being independently movable toward and away from the adjacent straight edge of the plate in an arcuate path concentric to the curvature of said plate.

17. In a machine for cutting the straight edges of curved plates of different arcuate widths, a cutter for each straight edge of the plate, each of said cutters being selectively movable into any one of a plurality of positions corresponding to different plate widths, and means to support each of said cutters, each support including means to guide the supported cutter in an arcuate path concentric to the curvature of the plate during the movement thereof into any selected position. 10

18. In a machine for cutting the straight edges of curved plates of different arcuate widths, a cutter for each straight edge of the plate, each of said cutters being selectively movable into any one of a plurality of positions corresponding to 15 different plate widths, means to support each of said cutters, each support including means to guide the supported cutter in an arcuate path concentric to the curvature of the plate during the movement of said cutter into any selected 20 position, and releasable means to locate and maintain each cutter in its selected position.

19. In a machine for cutting the straight edges of curved plates of different arcuate widths, a cutter for each straight edge of the plate, each 25 of said cutters being selectively movable into any one of a plurality of positions corresponding to different plate widths, means to support each of said cutters, each support including means to guide the supported cutter in an arcuate path 30 concentric to the curvature of the plate during the movement of said cutter into any selected position, releasable means to locate and maintain each cutter in its selected position, and means to adjust said releasable means to vary the cutter 35 locating effect thereof.

WILLIAM F. HUCK.
